UNITED STATES PATENT OFFICE.

WILLIAM A. JOHNSON, OF CHICAGO, ILLINOIS.

FOLDING TABLE.

Application filed February 21, 1921. Serial No. 446,887.

To all whom it may concern:

Be it known that I, WILLIAM A. JOHNSON, a citizen of the United States, and a resident of Chicago, in the county of Cook 5 and State of Illinois, have invented certain new and useful Improvements in Folding Tables, of which the following is a full, clear, and exact description.

The invention relates to folding tables and 10 more particularly to folding tables of the pedestal type, such, for example, as are used for serving means in rooms of hotels.

The object of the invention is to provide 15 an improved table which is provided with folding pedestals and simple means for securely locking the pedestals in operative position. A further object of the invention is to provide an improved pivotal connection between the pedestals and the table-top.

20 The invention consists in the several novel features hereinafter set forth and more particularly defined by claims at the conclusion hereof.

In the drawings: Fig. 1 is a perspective 25 of a table embodying the invention in operative position. Fig. 2 is a side elevation of the table in operative position. Fig. 3 is a section of the table in folded position. Fig. 4 is a section through one of the pedestals. 30 Fig. 5 is a detail section of one of the pivotal connections between pedestals and the table-top. Fig. 6 is a perspective of one of the pedestals and the slotted guide plate thereon. Fig. 7 is a section taken on line 35 7—7 of Fig. 6.

Adjacent each end and on the underside of a table-top 9 is secured a pair of blocks 10 in which the pedestals, one for each end of the table, are pivoted. Each pedestal 40 comprises a standard 11, feet 12 and a cross-bar 13, all rigidly secured together, corner-blocks 14 being employed to more firmly secure the standard to the cross-bars. Each cross-bar is disposed between one pair of 45 the blocks 10 and is pivotally connected thereto by means of pins 15 which have their inner ends driven into and thus frictionally secured in the cross-bar and their outer ends extending through bearing-plates 50 16 and into sockets 17 formed in the blocks 10. Bearing plates 16 are secured in recesses in the inner faces of the blocks respectively by screws 18. A washer 19 is interposed between each plate 16 and the adjacent end of the cross-bar 13. This pivotal 55 connection is one which may be readily assembled, avoids wear and can be produced at a low cost, it being understood that the pedestals and blocks 10 are usually formed of wood. In assembling the table, the 60 blocks 10 are secured to the table after the pedestals have been connected to the blocks.

The pedestals are adapted to swing into substantially parallel relation with the underside of the table and one is adapted to 65 overlie the other, the pivot between the cross-bar 13 of the underlying pedestal being positioned in offset relation with respect to the pedestal so that it will permit it to assume a position substantially parallel to 70 the table and spaced therefrom sufficiently for the other pedestal.

Each pedestal is adapted to be secured in operative position by a brace 20, one end of which is pivotally connected to the table, as 75 at 21, and the other end of which is provided with a stud 22 which is adapted to slide in a straight slot 23 formed in a plate 24 which is secured to one side of the pedestal. A head 22' holds the stud in its slot 80 23. The pedestal is grooved, as at 25, for the head of the stud. Plate 24 is secured to one side of a pedestal by screws 26. A locking device for each pedestal comprises a stud 27 which is slidably mounted in a 85 socket 28 which is secured in a pedestal and a spring 29 in said socket is adapted to press the stud outwardly. A stop-rod 30 is secured to each stud to limit its outward movement. The outer end of the stud is 90 rounded, as at 31, so that it may be forced inwardly against the force of spring 29 by the brace, the latter being provided with a bevelled portion 32 for this purpose. Each brace is provided with a hole 33 into which 95 the stud 27 is adapted to snap when the pedestal is in operative position, and with a hole 34 into which the stud will snap when the pedestal is in folded position. When it is desired to fold or unfold the table, it is 100 only necessary to press the studs 27 inwardly to release the braces and thereupon they will be free to swing from one position to the other. As the pedestals reach either 105 of their alternative positions, the studs 27 will automatically snap into the holes 33 or 34 and thus serve to automatically lock the pedestals in desired positions. When the pedestals are folded, they and the braces will be disposed close and parallel to the 110

table-top, so that the tables may be stacked when not in use.

The invention exemplifies a folding pedestal table with simple means for securely locking the pedestals in operative and folded positions and whereby the pedestals will be securely held to firmly support the table-top; and also pivotal connections between the pedestal and the table which are simple 10 in construction.

The invention is not to be understood as restricted to the details set forth, since these may be modified within the scope of the appended claims, without departing from 15 the spirit and scope of the invention.

Having thus described the invention, what I claim as new and desire to secure by Letters Patent, is:

1. In a folding table, the combination of 20 a top, pedestals pivotally connected to the top, braces pivotally connected to the top and slidably connected to the pedestals, and spring-pressed studs in said pedestals movable transversely to the braces and formed

to enter holes in said braces positively to 25 lock the latter in open position.

2. In a folding table, the combination of a top, pedestals pivotally connected to the top, braces pivotally connected to the top and slidably connected to the pedestals, and 30 spring-pressed studs in said pedestals movable transversely to the braces and formed to enter holes in said braces positively to lock the latter in both open and closed positions.

3. In a folding table, the combination of a top, pedestals pivotally connected to the top, braces pivotally connected to the table-top, slotted plates secured to the sides of the pedestals, sliding stud connections between the slots in said plates and said braces, 40 sockets in the pedestals, and spring-pressed studs in the sockets for automatically locking the plates and braces together, the braces being provided with holes to receive the 45 locking studs when the pedestals are in folded and operative positions.

WILLIAM A. JOHNSON.
